UNITED STATES PATENT OFFICE

158,746

DISPLAY DEVICE

Otto R. Hickman, Hamburg, N. Y.

Application December 8, 1948, Serial No. 150,034

Term of patent 14 years

(Cl. D80—9)

To all whom it may concern:

Be it known that I, Otto R. Hickman, a citizen of the United States, residing at 96 Buffalo Street, Hamburg, New York, have invented a new, original, and ornamental Design for a Display Device, of which the following is a specification, reference being had to the accompanying drawing, forming part thereof.

In the drawing:

Fig. 1 is a side elevational view of a display device, showing my new design.

Fig. 2 is an end elevational view thereof, the opposite end elevational view being substantially identical.

Fig. 3 is a top plan view thereof.

Fig. 4 is a side elevational view thereof, viewed from the opposite side as shown in Fig. 1.

Fig. 5 is a bottom plan view thereof.

I claim:

The ornamental design for a display device, as shown.

OTTO R. HICKMAN.
